UNITED STATES PATENT OFFICE.

JOHN DUXBURY, OF MANCHESTER, ENGLAND, ASSIGNOR TO G. & R. DEWHURST, OF SAME PLACE.

MACHINE FOR MARKING FOLDED WOVEN GOODS WITH TRADE-MARKS, &c.

SPECIFICATION forming part of Letters Patent No. 448,212, dated March 17, 1891.

Application filed January 4, 1889. Serial No. 295,438. (No model.) Patented in England December 6, 1879, No. 4,998.

To all whom it may concern:

Be it known that I, JOHN DUXBURY, merchant, a subject of the Queen of Great Britain and Ireland, and residing at Manchester, 5 county of Lancaster, England, have invented certain Improvements in Machines for Marking Folded Woven Goods with Trade-Marks and other Marks and Devices, (for which I have obtained a patent in Great Britain, No. 10 4,998, dated December 6, 1879,) of which the following is a specification.

My invention relates to the marking of folded woven goods in the pieces—as, for example, to the marking of cotton piece goods. 15 Such goods are generally marked on the outside fold of the piece with a trade-mark, and in most cases with additional marks or numbers. Previously to my invention the said marks have been impressed upon the piece by 20 means of stamps or blocks charged with color and operated by hand. To render the operation more expeditious and to obtain a superior effect are the objects of my invention. To this end I employ revolving engraved or 25 prepared rollers in lieu of the said stamps, and I arrange for the pieces of goods to be fed through a machine in which they receive the impressions from the rollers.

In a machine designed for the purposes of 30 my invention a bed-roller and a marking-roller are mounted in a suitable framing, the marking-roller being pressed toward the bed-roller by means of a yielding load. The marking-roller is engraved or prepared with the 35 required designs or marks *in intaglio* or in relief, as may be most suitable to the obtainment of the desired effect, and is supplied with color by ordinary or suitable means. The pieces of goods are fed up to the rollers 40 by means of an endless lattice-apron, which is actuated in unison with the rollers, and is formed or furnished with ledges, stops, or guides, to insure the correct laying of the pieces, so as to cause the design to be printed 45 in correct position on the pieces.

In the accompanying drawings, Figure 1 represents a cross-sectional elevation of my marking-machine. Fig. 2 is a back elevation of the same. Fig. 3 is a view of the cam for 50 imparting motion to the color-trough. Fig. 4 is a modification of the construction and ac-

tion of the apron. Fig. 5 is an enlarged side view of the color-trough and "doctor." Fig. 6 is an enlarged rear view of the same, also showing the actuating-cam. Fig. 7 shows an enlarged top view of the cam. Fig. 8 represents in section the manner in which the guides *x'* are adjustably secured upon the belt *x*.

In the drawings, *a a* are two standards, which are suitably connected together by 60 means of tie-rods to form the framing of the machine. In each standard is formed a slot, in which are fitted bearings for the journals of two rollers *b* and *c*. The roller *b* is made of copper or other suitable metal or material, 65 and is engraved, cut, or formed with the desired designs. The roller *c* is the bed-roller, which sustains the piece of goods against the pressure of the marking-roller. The roller-bearings are fitted to slide in the slots in the 70 standards, the bearings of the bed-roller being sustained by screws *d*, which are provided with hand-wheels, in order that they may be readily turned, so as to raise or lower the bearings, as may be desired. The 75 bearings of the upper roller are sustained by screws *e*, which engage with nuts *f*, which are mounted in levers *g*. The upper marking-roller is sustained in its bearings so as not to drop onto the lower roller in the intervals 80 between the passage of the pieces of goods between the rollers. Each lever *g* is hinged by one end to the framing, and is jointed at the other end to a connecting link or rod *h*, which extends to a second lever *i*. Each lever 85 *i* is hinged by one end to the framing, and sustains at the other end a load *k*. The levers *g* and *i* are so proportioned as to multiply the gravity of the load, so as to exert a powerful downward pressure upon the journals of the upper roller, as will be well understood. The distance of the two rollers may be regulated by turning the screws *e*. Upon one of the journals of the upper roller is fixed a spur-wheel *l*, with which gears a pinion 90 which is fixed upon a driving-shaft *m*, which is provided with fast and loose pulleys *n*, which furnish means whereby the rollers may receive motion. The two rollers are connected together by means of spur-wheels *o o*, which 95 are fixed upon the respective journals and gear together, so that the two rollers are caused 100

to revolve with a uniform surface speed. A doctor p is applied to the upper roller. This doctor is held by a metal clamp p' , which is formed with end pivots, which are mounted 5 in bearing-blocks r , which are carried by projections formed on or fixed to the upper roller-bearings. Each block r can be adjusted with regard to its distance from the roller by means of a screw. The doctor-clamp p' is furnished 10 with weighted arms q , which tend to press the edge of the doctor against the surface of the roller. The doctor is suitably packed at each end, or is provided with end pieces formed of felt or other suitable elastic material, 15 or faced with such material on the sides which are toward the roller, whereby is formed an open trough in which a supply of "color" or printing or marking composition may be placed. A to and fro endwise movement is 20 imparted to the doctor and clamp or color trough by means of a cam 1, which is fixed on one of the journals of the lower roller, and is indicated by dotted lines in Fig. 2 and shown separately in Fig. 3. This cam 1 acts 25 upon a bowl 2 upon a lever 3, to which is jointed one end of a rod s , which is connected by the other end to the doctor-clamp. The arrangement is adapted for the cases wherein a marking-roller formed with an engraved or 30 sunk design is employed. As the roller revolves, the color enters into the sunk lines forming the design, the doctor preventing the transmission of color by the smooth surface of the roller. I prefer to apply a brush or 35 cleaning-rubber (indicated by u) to the roller. In the example a brush is hinged to blocks which are adjustable upon the roller-bearings, as in the case of the doctor-clamps. The brush is caused to press upon the surface of the 40 roller, (so as to clean the same,) by means of screws v , which bear upon the roller-bearings and engage with arms projecting from the brush, or any other suitable means for effecting the same object may be used. Brackets 45 4 on the standards a carry the bearings of two shafts $w w'$, upon which are fixed wheels, rollers, or parts which sustain and give motion to an endless traveling apron x . In the example the shaft w is connected by means of spur-gearing y 50 with the shaft of the upper roller, so that when the said roller revolves the upper surface of the apron is caused to travel toward the rollers. The apron is furnished with guides x' . These guides are simply screwed 55 to the wood slats of the belt x by means of ordinary screws, and can be removed from one slat and screwed onto another slat quite independently of the adjustment of the belt x . The machine is used in the following manner: 60 The pieces of goods to be marked (indicated by A) are placed successively upon the apron with one edge of the piece in contact

with or at an arranged distance from the guides x' . Each piece so placed is carried forward by the apron until it is seized by the 65 rollers, which then carry the piece onward, at the same time imprinting the design upon the piece, the adjusted position of the guides x' causing the design to be correctly placed upon the piece. The piece so marked passes onto 70 a sloping table z or onto a suitable receiving-table or part, from which it may be removed by an attendant. I may modify the construction and action of the apron—as, for example, I may employ an apron formed of leather, 75 felt, or other suitable material, and arranged for the upper carrying surface to pass with the piece between the two rollers, and to deliver the piece at the back of the machine, the apron returning below the bed-roller to 80 the front of the machine, as shown at Fig. 4. The apron may carry any suitable indications in lieu of the projecting guides x' .

What I claim is—

1. In apparatus for marking folded woven 85 piece goods with trade-marks and other marks and devices, the combination of the marking-roller b , supplied with color from the color-trough, with the bed-roller and the endless traveling apron x , having the adjustable 90 guides x' for carrying forward the folded pieces to the rollers, substantially as described and shown.

2. In apparatus for the purpose set forth, the combination of the marking-roller b , supplied with color, the bed-roller c , and the endless traveling apron x , having a supporting and actuating roller upon each side of said bed-roller c , and passing with the goods between the two rollers, and holding and supporting the goods beneath the point where the impression takes place, substantially as set forth.

3. In apparatus for the indicated purpose, the combination of the traveling apron x , the 105 rollers b and c , the screws d and e , nuts f , engaged by the latter, the presser-levers g , mounted on said nuts, rod h , levers i , and the delivery-table z , substantially as described and shown.

4. In apparatus for the indicated purpose, the combination of the roller b , the trough, the weighted arms q , and the doctor p with the cam 1, the bowl 2, the lever 3, and the rod s for actuating the color-trough, substantially as described and shown.

In testimony whereof I have signed my name to this specification in the presence of two subscribing witnesses.

J. DUXBURY.
